(57) **CLAIM**

The ornamental design for a “bottle sling”, as shown and described.

DESCRIPTION

FIG. 1 is a front elevational view of our bottle sling design; FIG. 2 is a right side view, the left side being a mirror image thereof;

FIG. 3 is a rear elevational view thereof;

FIG. 4 is a top plan view thereof; and,

FIG. 5 is a bottom plan view thereof.

The broken lines showing a buckle, a bottle and a dispensing cap are for illustrative purposes only and do not form part of the claimed design.
